UNITED STATES PATENT OFFICE

135,225

DESIGN FOR A FLASHLIGHT OR SIMILAR ARTICLE

Lynn Brodton, Collingswood, N. J., assignor to Flashlight Company of America, Jersey City,
N. J.

Application April 28, 1941, Serial No. 100,661

Term of patent 14 years

To all whom it may concern:

Be it known that I, Lynn Brodton, a citizen of the United States and a resident of Collingswood, in Camden County, State of New Jersey, have invented a new, original, and ornamental Design for a Flashlight, or Similar Article, of which the following is a specification, reference being had to the accompanying drawing, forming a part thereof, in which

Figure 1 is a side elevational view of a flashlight, or similar article, showing my new design;
Fig. 2 is a front elevational view thereof;
Fig. 3 is a rear elevational view thereof; and
Fig. 4 is a top plan view thereof.

I claim:

The ornamental design for a flashlight, or similar article, as shown.

LYNN BRODTON.
